W. C. CARPENTER

BUCKLE

Filed Oct. 5, 1925

William C. Carpenter
INVENTOR

BY Victor J. Evans

ATTORNEY

WITNESS: J. J. L. Wright

UNITED STATES PATENT OFFICE.

WILLIAM C. CARPENTER, OF OAKLAND, ILLINOIS.

BUCKLE.

Application filed October 5, 1925. Serial No. 60,595.

This invention relates to improvements in buckles and especially to that form of buckle known as "belt buckles" and which contemplates the provision of a spring clip formed 5 upon the inner plate of the buckle in securing and holding a buckle in place upon the outer portion of a trousers fly whereby the buckle will be prevented from accidental displacement thereon and remain in the same 10 position when the trousers to which the invention is applied are in use or not.

Another object of my invention resides in the construction of a grip mounted longitudinal sliding movement within a buckle 15 and exposing a rolled grooved surface around a pivot pin for facilitating the sliding movement thereof and which further includes an upwardly extending edge of the plate so firmly gripped which also exposes a 20 grooved portion toward that portion of the belt inserted within a buckle in preventing the latter from sliding rearwardly with respect to the buckle when so gripped.

With the above and other objects in view, 25 the invention further includes the following novel features and detail of construction to be hereinafter fully described, illustrated in the accompanying drawing and pointed out in the appended claims.

30 In the drawing:—

Figure 1 is a fragmentary front elevation of a trousers fly showing my present invention applied thereto.

Figure 2 being a sectional view taken 35 through a fly with the invention applied.

Figure 3 is a longitudinal sectional view taken through my invention per se when in use.

Figure 4 is a bottom plan view of the 40 buckle.

Figure 5 is a perspective of the grip.

Figure 6 is a similar view with a locking means for the belt upon the buckle.

Figure 7 is a diagrammatic plan view of 45 the bottom plate and the spring clip.

Referring to the drawing in detail, wherein like characters of reference denote corresponding parts, the reference character 10 indicates a fragmentary portion of a fly constituting the upper portion of a pair of trousers, not shown, it being of the usual

well known construction and forming no part of the present application for letters patent, but merely shown for the purpose of illustration in bringing forward the novel 55 advantages of the above entitled invention.

The invention residing in the provision of a buckle constituting a bottom plate 11 having a reduced end curved spring plate 12 formed integrally upon one end thereof and 60 bent rearwardly thereupon and having frictional engagement with the inner side thereof whereby the outer portion of the fly 10 may be engaged therebetween for a purpose 65 which will be presently apparent.

The opposite end of the bottom plate 11 forming inwardly inclined tapered portions 13 terminating in oppositely and outwardly disposed apertured ears 14 capable of being 70 bent forwardly with respect to the bottom plate 11 for the reception of trunnions 15 formed upon the opposite ends of a substantially L-shaped plate 16 exposing a row of gripping teeth 17 upon the offset portion thereof in retaining and fixing one end of 75 a belt 18 thereto. The adjacent marginal edges of the bottom plate 11 having a plurality of spaced parallel openings 19 arranged therein for registration and insertion 80 of ears 20 formed upon the inwardly offset edges 21 of a belt face or front plate 22.

In order to provide a locking means for the opposite end of the belt 18 within a space thus defined between the front plate 85 22 and the bottom plate 11, I provide upwardly and outwardly registering slotted portions 23 within the offset side edges 21 of the face plate 22 within which being mounted for sliding movement a pin 24 having heads 25 provided upon its opposite ends 90 exteriorly of the slotted portions 23.

Encircling that portion of the pin 24 within the face plate 22 is the rolled portion 26 of the plate 27 exposing longitudinal disposed grooved portions 28 upon the outer surface thereof while the remaining portion of the plate being curved upwardly in exposing a groove 29 within the edge thereof whereby the opposite end of the belt 18 while the curved end portion of the plate exposing 100 and having its grooved edge 29 engage the corresponding side of the belt 18 to prevent

the movable end of the belt 18 from sliding rearwardly with respect to the position at which it was originally locked.

It will thus be seen from the foregoing description and the accompanying drawing that this invention provides an exceedingly useful and advantageous buckle which will be greatly appreciated by belt wearers in so far as the spring clip 12 will retain the buckle as completed, upon the fly of a pair of trousers at a desired position and so rigidly as to prevent any accidental displacement thereof whether in use or not, and greatly overcoming the difficulty, nuisance and discomfort of having the buckle ride upwardly and above the fly and waist band of the trousers against the shirt which frequently causes sores around the abdomen owing to the rubbing action of the buckle 20 against that portion of the user's body.

It is further to be noted that the gripping means of the buckle for a belt exposing two gripping surfaces is capable of eliminating any possibility of a rearward sliding movement of that portion or point in the length of the belt so inserted within the face plate of the buckle while in use.

The invention is susceptible of various changes in its form, proportions and minor details of construction, and the right is herein reserved to make such changes as properly fall within the scope of the appended claims.

Having described my invention, what is claimed is:—

1. A belt buckle, a bottom plate having a spring clip formed integral therewith and bent upon itself against the inner side thereof in retaining the latter as a whole upon the upper portion of a trousers fly, a locking means arranged upon the opposite end of the bottom plate in securing one end of a belt thereto, and means slidably mounted within a buckle for rigidly and detachably securing the opposite end of the belt so inserted within the buckle.

2. A belt buckle of the character described comprising a bottom plate having a curved spring clip formed integral therewith upon one end and bent upon itself against the inner side thereof whereby the upper portion of a trousers fly may be inserted therebetween in retaining the buckle at a desired portion upon the fly, the opposite end of the bottom plate having an angular locking plate mounted thereon for securing one end of a belt thereto, a face plate arranged upon the forward side of the bottom plate, and means slidably mounted within the face plate for rigidly and detachably securing the opposite end of a belt so inserted within the buckle.

3. A belt buckle of the character described comprising a bottom plate having a curved spring clip formed integral therewith upon

one end and bent upon itself against the inner side thereof whereby the upper portion of a trousers fly may be inserted therebetween in retaining the buckle at a desired portion upon the fly, the opposite end of the bottom plate forming spaced parallel apertured ears upon the forward side thereof, an offset locking plate having trunnions formed upon its opposite end for insertion within the apertures of the ears and exposing a row of gripping teeth upon the offset edge thereof in securing one end of a belt thereto, a face plate arranged upon the forward side of the bottom plate and having registering inclined slotted portions provided in the adjacent side walls thereof, and a locking pin mounted for sliding movement within the slotted portions for rigidly and detachably securing the opposite end of the belt so inserted within a buckle.

4. A belt buckle of the character described comprising a bottom plate having a curved spring clip formed integral therewith upon one end and bent upon itself against the inner side thereof whereby the upper portion of a trousers fly may be inserted therebetween in retaining the buckle at a desired portion upon the fly, the opposite end of the bottom plate forming spaced parallel apertured ears upon the forward side thereof, an offset locking plate having trunnions formed upon its opposite end for insertion within the apertures of the ears

90 thereof in securing one end of a belt thereto, a face plate arranged upon the forward side of the bottom plate and having registering inclined slotted portions provided in the adjacent side walls thereof, and a locking pin mounted for sliding movement within the slotted portions for rigidly and detachably securing the opposite end of the belt so inserted within a buckle.

95 5. A belt buckle of the character described comprising a bottom plate having a curved spring clip formed integral therewith upon one end and bent upon itself against the inner side thereof whereby the upper portion of a trousers fly may be inserted therebetween in retaining the buckle at a desired portion upon the fly, the opposite end of the bottom plate forming spaced parallel apertured ears upon the forward side thereof,

100 an offset locking plate having trunnions formed upon its opposite end for insertion within the apertures of the ears and exposing longitudinal rows of gripping surface upon and against the inner side of the opposite end of the belt so inserted within a buckle.

105 6. A belt buckle of the character described comprising a bottom plate having a curved spring clip formed integral therewith upon one end and bent upon itself against the inner side thereof whereby the upper portion of a trousers fly may be inserted therebetween in retaining the buckle at a desired portion upon the fly, the opposite end of the bottom plate forming spaced parallel apertured ears upon the forward side thereof,

110 an offset locking plate having trunnions formed upon its opposite end for insertion within the apertures of the ears and exposing a row of gripping teeth upon the offset edge thereof in securing one end of a belt thereto, a face plate arranged upon the forward side of the bottom plate and having

115 registering inclined slotted portions provided in the adjacent side walls thereof, and a locking pin mounted for sliding movement within the slotted portions for rigidly and detachably securing the opposite end of the belt so inserted within a buckle.

120 7. A belt buckle of the character described comprising a bottom plate having a curved spring clip formed integral therewith upon one end and bent upon itself against the inner side thereof whereby the upper portion of a trousers fly may be inserted therebetween in retaining the buckle at a desired portion upon the fly, the opposite end of the bottom plate forming spaced parallel apertured ears upon the forward side thereof,

125 an offset locking plate having trunnions formed upon its opposite end for insertion within the apertures of the ears and exposing a row of gripping teeth upon the offset edge thereof in securing one end of a belt thereto, a face plate arranged upon the forward side of the bottom plate and having registering inclined slotted portions provided in the adjacent side walls thereof, and a locking pin mounted for sliding movement

within the slotted portions, a plate having one end bent upon itself and encircling that portion of the locking pin within the buckle and exposing spaced parallel longitudinally disposed grooves upon and against the inner side of the opposite end of the belt so inserted within the buckle, and the opposite end of the plate curving outwardly and expos-

ing grooved portions thereon for a simultaneous gripping action upon the inner side ¹⁰ of the belt in eliminating any possibility of the accidental rearward sliding movement of the belt so inserted within the buckle.

In testimony whereof I affix my signature.

WILLIAM C. CARPENTER.
